CEDAR BOARD

Application filed May 23, 1930. Serial No. 455,048.

This invention relates to cedar boards, and an object of the invention is to provide a board composed entirely, or mainly, of shavings, sawdust or fibre of cedar or other aromatic woods for lining clothes closets, or for making or lining cedar boxes.

The purpose of the invention is to provide a board of this character which will give an aromatic odor, to protect clothing and the like from moths or other insects, and which can be manufactured and sold at a reasonably low price.

In carrying out the invention we preferably provide the board with a backing of paper, composition board or any other material, the function of the paper being to confine the aroma of the material to the inside of a closet, box, chest, room and the like.

In making the board we utilize cedar or other suitable aromatic wood, in particles, which are pressed together with a suitable adhesive, and the backing constitutes a permanent part thereof wherever the backing is employed.

With these and other objects in view, the invention consists in certain novel features of construction and combinations and arrangements of parts, which will be more fully hereinafter described and pointed out in the claim.

In the accompanying drawing—

Figure 1 is a perspective view showing one form of our improved board;

Figure 2 is an exaggerated fragmentary section of the board shown in Figure 1; and

Figure 3 is a view similar to Figure 2, showing a relatively thin board with a thicker backing, such as composition board.

1 represents our improved board, and 2 a backing therefor. The board 1 is composed of shavings, sawdust or fibre of cedar or other suitable aromatic wood, which is pressed together with a suitable adhesive so as to form a strong, durable board, through which a nail may be driven so as to utilize the board wherever any other board might be used.

On this board 1 we preferably provide a backing 2, which may be of paper or card-board or composition board, as indicated

by Figure 3 of the drawing. When paper is used its function is to keep the aroma of the board within the box, closet or room, and where composition board is used it has the added function of giving strength to the board.

A board of this character can be manufactured and used much more cheaply than an ordinary cedar board, and it has a wide range of utility.

What is claimed is:

An aromatic board composed of fragments of aromatic wood pressed together to form a strong sheet, and a backing constituting an odor insulator secured against one side only of the board or sheet.

JOHN FREDERICK MAHLSTEDT.
